UNITED STATES PATENT OFFICE.

FREDERICK L. BRAENDER, OF MONTCLAIR, NEW JERSEY, ASSIGNOR TO BRAENDER RUBBER & TIRE CO., OF RUTHERFORD, NEW JERSEY, A CORPORATION OF DELAWARE.

DESIGN FOR AN AUTOMOBILE TIRE.

Application filed September 26, 1922. Serial No. 3,825. Term of patent 14 years.

To all whom it may concern:

Be it known that I, FREDERICK L. BRAENDER, a citizen of the United States, residing at Montclair, in the county of Essex and State of New Jersey, have invented a new, original, and ornamental Design for Automobile Tires, of which the following is a specification, reference being had to the accompanying drawings, forming a part thereof, wherein—

Figure 1 is a plan view of a portion of an automobile tire showing my new design, and

Figure 2 is a transverse sectional view of the same on line 2—2 of Figure 1.

I claim:

The ornamental design for an automobile tire, as shown.

FREDERICK L. BRAENDER.
